UNITED STATES PATENT OFFICE.

LEONARD C. HECTOR AND CHARLES E. DAVIS, OF TORONTO, ONTARIO, CANADA, ASSIGNEES OF ONE-THIRD TO ROBERT H. McFARLAND, OF TORONTO, ONTARIO, CANADA.

DESIGN FOR AN ELECTRIC FIRE-LOG.

52,318.

Specification for Design.

Patented Aug. 27, 1918.

Application filed February 25, 1918. Serial No. 219,144. Term of patent 3½ years.

To all whom it may concern:

Be it known that we, LEONARD C. HECTOR and CHARLES E. DAVIS, citizens of the United States, residing at Toronto, Province of Ontario, Dominion of Canada, have invented a new, original, and ornamental Design for Electric Fire Logs, of which the following is a specification, reference being had to the accompanying drawing, forming part thereof.

The figure is a front elevation of an electric fire log showing our design.

We claim:

The ornamental design for an electric fire log as shown.

LEONARD C. HECTOR.
CHARLES E. DAVIS.
